PROCESS FOR THE CONTINUOUS RECOVERY OF GLYCERIN FROM SOAP

Benjamin H. Thurman, Bronxville, N. Y., assignor to Refining, Inc., Reno, Nev., a corporation of Nevada

Application June 14, 1937, Serial No. 148,240

11 Claims. (Cl. 260—418)

This invention relates to a process for the treatment of soap and more particularly to a process in which a mass of soap made in a kettle, or otherwise, is processed to remove volatiles therefrom.

In the commercial manufacture of soap a mixture of soap and water is produced. If glycerides are employed as the saponifiable material, this mixture also contains glycerin. The removal and recovery of the glycerin from soap mixtures, as heretofore practiced, is more difficult and time consuming than the original preparation of the soap mixture. In prior processes, a strong salt solution is added to the mixture in order to throw the soap out of the solution while at the same time dissolving the glycerin. Then, after the salted mixture has been boiled for a considerable time, it is allowed to settle for several hours. The soap lye which separates contains much of the glycerin but a portion remains associated with the soap. To further purify the soap and remove additional glycerin therefrom, it is necessary to repeatedly subject the soap to washing or salting out operations.

Also the recovery of the glycerin from the soap lye from prior process requires a long and complex process. It usually involves chemical treatment followed by evaporation of water, resulting in an appreciable loss of glycerin. The crude glycerin thereby obtained has to be further treated by distillation and other processes, resulting in additional loss of glycerin, before a commercially pure glycerin is obtained.

The soap mass after the glycerin has been withdrawn therefrom is then treated to remove moisture if a solid or powdered soap is obtained. The various processes of removing this moisture are also expensive and time consuming. The present invention eliminates all of these difficulties and rapidly produces extremely pure glycerin and soap in marketable form.

In accordance with the present invention, the glycerin and water are removed from a soap mixture by vaporizing the same and the soap can be recovered in substantially anhydrous and glycerin-free form. This process of separating glycerin from the soap is continuous and large quantities may be treated in a relatively short time.

It is, therefore, an object of the invention to provide an improved process of separating volatiles from soap mixtures such as are produced in the manufacture of soap.

Another object of the invention is to provide a continuous process of recovering glycerin of high purity from soap mixtures.

In addition the soap mixture can by the present process be subjected to temperatures and pressures far in excess of those possible in the conventional methods of processing soap mixtures even if no glycerin is present or it is not desired to recover the same. By such high temperatures various colored and odorous impurities contained in many soap making materials, for example, higher alcohols such as sterols, may be vaporized and the vapors separated from the soap in an evaporating zone thus producing a purer soap. Also many insoluble impurities which ordinarily color the soap or later break down to give the soap an undesirable odor, for example, insoluble proteinaceous materials, are broken down by the high temperatures, capable of being employed in the present process, into non-odorous or colorless compounds or rendered vaporizable or soluble so that they may be removed by evaporation or washed out of the resultant soap. Thus very low grade soap mixtures, such as cottonseed or other soapstock resulting from refining operations or soap mixtures made from low grade fats, can be treated by the present process to produce much lighter colored and better grades of soap than can be made by conventional processes. The high temperature treating step may be of such short duration that the soap is not injured even though prolonged treatment of the soap at the high temperature would decompose the same.

It is, therefore, another object of the invention to subject a soap mixture to high temperatures in order to vaporize or break down colored and odorous impurities.

A still further and quite important object of my invention is to provide a process wherein saponification may be effected in a kettle, for example, under relatively low temperatures and for a relatively long period of time after which the resulting mixture, including soap, glycerin and water is continuously and quickly passed through a heating zone where it is subjected to an elevated temperature for a short period of time before continuously discharging it into a vacuum chamber where the glycerin, water and other materials are vaporized therefrom and separately condensed while the soap is discharged from the vacuum without breaking the same.

Still more specifically, the invention comprehends the employment of a pumping mechanism interposed between the relatively large kettle containing the saponified or partially saponified product and the coil, constituting the heating zone, for performing the dual function of forcing the saponified mixture through the coil at

5 a substantial rate of flow to maintain the mixture while it is subjected to high temperatures and of more thoroughly mixing the saponified material, thereby providing for contact between any unsaponified material and saponifying agent to further the saponification before the mixture reaches the high temperature zone.

10 Other objects and advantages of the invention will appear in the following description of the preferred embodiments of the invention which are described in connection with a schematic drawing of a suitable apparatus, of which:

15 Figure 1 is an assembly view of the entire apparatus, and;

20 Figure 2 is a fragmentary view in section showing an arrangement of nozzles in the evaporating chamber.

25 Referring to the drawing, 10 indicates, in general, apparatus suitable for carrying on a saponification step; 11 indicates a heating device for heating a soap mixture; 12 indicates in general an evaporating chamber which is provided with a conveyor system indicated at 13 for removing soap from the evaporating chamber; and 14 indicates a condensing system for condensing glycerin and water vapors.

30 The apparatus 10 for making soap mixture may include conventional soap kettles 15 and 16, provided with heating jackets 17 through which steam or other heating medium may be passed by the pipe 18. Pipes 19 and 20 are provided for introducing a measured quantity of a saponifiable material and a saponifying reagent, respectively. These materials are mixed in the kettle by an agitator 21 driven by a motor 22 while the materials are heated by the steam jacket 17. The saponifying reagent, which is usually a caustic alkali, reacts with the saponifiable material to form a soap mixture. Duplicate kettles will ordinarily be provided so that soap can be made in one kettle while the soap mixture is being withdrawn from the other and processed. Instead of making the soap mixture in the kettles illustrated, it may be produced in other apparatus and delivered to the kettles from which it is supplied to the remainder of the process.

35 For withdrawing the soap from either kettle, pipes 23 and 24 leading from the bottoms of the kettles are provided and are connected to a pipe 25 leading to a pump 26. Valves 27 and 28 are positioned in the pipes 23 and 24, respectively, in order to provide for withdrawing soap from either kettle. Also a pipe 29 connected to pipes 23 and 24 through valves 30 and 31 may be employed 40 for diverting portions of the soap mixture to other processes or for cleaning purposes. The soap mixture in the kettles should be maintained in substantially uniform admixture during withdrawal of the same as, for example, by the 45 agitators 21 or by passing steam through the mixture, and should be rendered sufficiently fluid to enable it to be pumped through the process by heating or dilution.

50 Pump 26 may be any type of pump suitable 55 for forcing the soap mixture under a relatively high pressure through a heating coil 32 positioned in a casing 33 forming part of the heating device 11. Heat may be applied to the coil by any suitable means, for example, by a burner 34 in 60 the lower portion of the casing 33. In order to control the amount of heat applied to the coil a suitable thermostatic device 35 may be employed 65 for controlling the amount of fuel delivered to the burner 34. Such a device may include a 70 member 36 into which the heated materials from

75 the coil 32 are delivered by the tube 37 so that these materials flow in contact with the walls of the member 36 and are discharged through a pipe 38. In the device shown, the products of combustion from the burner 34 also contact the member 36 so that the temperature of this member is determined by both the temperature of the materials discharged from the coil 32 and that of the products of combustion. A valve 39 is connected to one end of the member 36 so that expansion due to increase in temperature of this member partially closes the valve to reduce the flow of fuel to burner 34. Likewise a decrease in temperature of the member 35 increases the flow of fuel to burner 34. The normal position of the valve 39 can be controlled by a hand-wheel 40 mounted upon shaft 41 rotatively attached to one end of the member 35 and screw-threaded through a member 42 attached to the casing 33. By adjusting the hand-wheel 40, any desired temperature of the materials discharging from the coil 32 can be automatically maintained.

10 Any desired pressure may be imposed upon a mixture in the coil 32 by the pump 26 and this pressure may be maintained by valve 43 in the 15 pipe 38 or by a restricted discharge orifice in the nozzles 44 positioned in the evaporating chamber 12. Alternatively, if desired, the diameter of the 20 tube forming the coil 32 may be made sufficiently small to maintain the desired pressure.

15 If glycerin is to be recovered, the soap mixture is heated in the coil 32 to a sufficient temperature to cause the glycerin thereof to be 25 vaporized when discharged into the evaporating chamber 12 and is maintained out of contact with the atmosphere in its heated state. As herein-after explained, the pressure and temperature in the coil 32 may be regulated, if desired, so that 30 water or glycerin vapors are generated in the coil 32. The pressure at the discharge end of the coil will depend upon the temperature employed 35 so as to secure the desired amount of vaporization in the coil.

20 The evaporating chamber may include an inner 40 casing 45 closed to the atmosphere and having a 45 heating jacket 46 positioned therearound. Steam or other heating medium may be admitted to the 50 heating jacket 46 through a pipe 47 and the heating jacket is preferably surrounded by an insulating covering 48. It has been found advantageous 55 to direct the mixture discharge from the nozzles 44 against the heated walls of the evaporating chamber so that the mixture flows down these walls in a relatively thin film and the glycerin and water vapors are more easily liberated. A preferred 60 arrangement of the nozzles 44 to accomplish this purpose is shown in Fig. 2. It will be noted that the liberated vapors are not required to pass through a spray of material delivered into the 65 evaporating chamber to reach the vapor pipe 49 but have a substantially unimpeded path upwardly through the central portion of the chamber. By this arrangement entrainment of liquid or solid materials in the vapors leaving the 70 evaporating chamber is substantially eliminated. The vapors present in the evaporating chamber 45 are withdrawn through the pipe 49 and entrainment separator 49' to a condenser 58 provided with a receiver 51. The entrainment separator 49' removes any traces of solid or liquids in 75 the vapors and returns them through a pipe 58' to the evaporating chamber. The entrainment separator is preferably provided with a heating jacket 51' to prevent condensation of glycerin 80 therein. In the condenser 51 most of the glycerin 85

vapors are condensed and glycerin flows into the receiver 51 while the water vapors are withdrawn from the receiver 51 through a pipe 52 to a water condenser 53 in which they are condensed and the resulting water flows into a receiver 54. A vacuum pump 55 withdraws undenended vapors from the receiver 54 and maintains a vacuum throughout the condensing system 14 and evaporating chamber 45. Suitable cooling means (not shown) may be provided for the condensers 50 and 53 and the temperature therein controlled so that fractional condensation of the water and glycerin takes place. A fractionation column may be employed instead of separate condensers, if desired. The condensate from the various receivers may be removed through the pipes 56 and 57, for example, by pumps (not shown). A small portion of glycerin ordinarily is found admixed with the water in receiver 51 and this water may be employed as part of the water in the saponification step so that the glycerin is subsequently recovered in the process. A greater number of condensers may be provided if a greater number of condensate fractions are desired.

The heating jacket 46 around the evaporating chamber 45 supplies additional heat for vaporizing glycerin and in some instances it is desirable to furnish still more heat by injecting steam, preferably superheated, into the evaporating chamber by a pipe 60. This steam also has a further function of assisting in liberating the glycerin vapors from the soap and carrying them to the condensing system 14.

In order to remove substantially all of the glycerin from the soap, the temperature in the evaporating chamber 45 must usually be sufficient to cause the soap to be in a molten or plastic condition, although the soap may deposit in the bottom of the evaporating chamber in a powdered form with certain types of fat, particularly if the conditions are such that all of the glycerin is not vaporized. However, if glycerin is to be evaporated, the soap collecting in the bottom of the chamber 45 is at a temperature such that contact with the atmosphere will cause deterioration. The soap must be promptly removed from the evaporating chamber as the temperature therein is sufficient to cause deterioration of the soap if it is maintained at this temperature for a prolonged length of time. It is, therefore, necessary to promptly remove the soap and cool the same before it is allowed to come in contact with the atmosphere.

A suitable apparatus for this purpose is the conveyor system 13. This system may include a screw conveyor 61 having a casing 62 opening into the bottom of the evaporating chamber 45. The inclined walls 63 of this chamber direct the soap into the conveyor casing 62. Jackets 64 and 65 surround the conveyor casing 62 for heating or cooling the same. Either a cooling medium or heating medium may be passed through the jacket 65 depending upon the temperature of the soap in the conveyor. It is necessary that the soap be sufficiently solid before leaving the conveyor system that it effectively plugs the discharge from the conveyor and in some cases this may require cooling by the jacket 65, although ordinarily a heating medium will be passed through this jacket in order to help maintain the temperature in the evaporating chamber 45. A cooling medium is passed through the jacket 64 in order to cool the soap. Also the conveyor shaft 66 may be made hollow and may be provided with an inner pipe 67 so as to enable a

heating or cooling medium to be introduced through the pipe 67 and discharged through the pipe 68 connected to the pipe 67 through a suitable packing gland 68'. This last means provides an extremely sensitive device for controlling the temperature of the soap being discharged by the conveyor 61. In order to assist in causing the soap to be discharged by the conveyor 61, stationary members 69 extending through the conveyor casing may be provided to prevent the soap mass from turning with the conveyor. Slots 70 are provided in the screw portion of the conveyor to receive the members 69. It has been found advantageous to enlarge the conveyor shaft adjacent the discharge end as at 69', in order to provide a tapered and restricted discharge passage to assist in causing the soap mass to seal the conveyor against entrance of air to maintain the vacuum in the evaporating chamber. The sealing of the conveyor may also be assisted by reducing the pitch of the screw adjacent the discharge end thereof as shown in the drawing.

In order to further cool the soap it may be forced through a grid, indicated at 71, formed of small tubes passing through the discharge portion 25 of the conveyor 61. The grid 71 also assists materially in maintaining a seal for the vacuum in the chamber 45. It has been found that additional vapors can be withdrawn from the conveyor casing 62 by a vent 72, preferably leading 30 to the vapor pipe 49.

Preferably the conveyor 61 discharges into a second conveyor 73 positioned at right angles thereto and provided with a cooling jacket 74 although a single conveyor may, in some instances, be sufficient. This conveyor may be of the same type as conveyor 61 and discharges through a valve 75 to the atmosphere. This valve is employed in starting up the apparatus in order to maintain a vacuum in the chamber 45 before 40 the conveyor system becomes filled with soap. The conveyor shafts are rotated by means of the sprockets 76 and are provided with bearings 77 adjacent the sprockets, but no bearings need be employed at the discharge end of the conveyors. 45 A pipe 77', leading into the inlet end of the second conveyor 74 may be provided for the introduction of other materials into this conveyor for admixture with the soap therein. The conveyor screw moves the soap away from this portion of the conveyor so that a low pressure space is provided for the introduction of materials. Thus water for rehydrating the soap to any desired extent or perfume or soap builders or fillers may be introduced and mixed with the soap.

In carrying out the process of the present invention a batch of soap is made in one of the kettles 15 or 16 or other suitable apparatus and delivered by the pump 26 to the heating device 11. The temperature during saponification and the proportions of materials used may be those known to the prior art. Thus, temperatures in the order of 150 to 212° F. may be employed or even higher temperatures up to, for example, 450° F., if closed receptacles are provided so that saponification is under pressure, may be employed in the saponification step without danger of injuring the soap or soap making materials. The agitation should be continued during withdrawal of the soap mixture in order to maintain the mixture substantially uniform. The pump 26 not only provides pressure for forcing the materials through the heating device and into the evaporating chamber 45 but also aids in further mixing the materials passed therethrough.

- The coil 32 has been found to provide efficient heating without local overheating, but any other type of heating device in which the materials can be heated to a high temperature and under pressure without local overheating may be employed. Also the thermostatic device 35 performs a further mixing function immediately before the materials are delivered into the evaporating chamber 45, although any other type of mixing device 10 may be substituted therefor and in many instances such mixing has been found to be unnecessary. The temperature to which the materials are raised in the heating device will depend upon the type of glyceride or fat being 15 treated, and in general these temperatures will be between 450° and 620° F. As has been indicated before, it is generally necessary to have the soap deposited in the evaporating chamber in a molten or plastic condition in order to satisfactorily recover the glycerin, and for this purpose 20 the temperature of the mixture introduced into the evaporating chamber should be sufficiently high to produce such molten or plastic soap. Even if glycerin is not present or is not recovered, it 25 may be desirable to employ temperatures in the upper portion of the above range in order to vaporize or break down impurities in the soap. It is important that the material subjected to the higher temperatures be substantially completely 30 saponified as such temperatures, in many cases, tend to discolor glycerides and fatty acids.
- In many cases, soap mixtures from commercial soap making processes may contain unsaponified fatty acids or glycerides occluded in soap 35 masses or particles and these may even be present in the finished soap from prior processes. The present invention is particularly adapted for handling such soap mixtures since the rapid flow through at least the first part of the heating 40 zone along with the passage of the material through the soap pump and connecting pipes breaks down any agglomerations of soap and unsaponified material and enables the unsaponified material to be substantially completely saponified.
- Even in cases where fatty acids are employed as the saponifiable material so that no glycerin is present in the soap mixture or it is desired to leave glycerin in the treated soap, a higher temperature is employed in the heating zone than 45 that used in the saponification step. This temperature must be sufficient to rapidly vaporize the water either in the heating zone or in the evaporating chamber and the present process provides for rapidly heating the soap mixture to 50 this temperature so that the soap mixture is not subjected to the higher temperature for prolonged periods of time. Thus the saponification step may be carried on by heating to relatively low temperatures over considerable periods of time 55 so as to obtain substantial saponification without danger of injuring the soap or saponifiable material by high temperatures. The temperature may then be rapidly raised in the heating zone and the volatiles promptly removed so that the 60 soap mixtures are subjected to the higher temperature for a brief period as compared to the time of treatment in the saponification step. A period of 2 to 5 minutes is usually sufficient for the entire heating step. The temperatures necessary to vaporize the water do, however, accelerate the saponification reaction and even the short period of treatment at the higher temperatures, accompanied by rapid flow of the soap mixture, substantially completes the saponification 65 of the unsaponified materials. Because of

the rapid saponification in the heating zone, partial saponification only may be accomplished in the prior saponification step and excellent results obtained by completing the saponification in the heating step. If unsaponified fatty acids or glycerides are present at the highest temperature in the heating zone, this temperature should not be above the "flash point" of the unsaponified materials.

When the temperature is raised above this flash point, as is usually necessary to vaporize glycerin, care should be taken that saponification is substantially complete before this temperature is reached, since such temperatures are likely to discolor unsaponified fatty acids or glycerides as above indicated. Even in this case, however, the first or lower temperature portion of the heating zone may be employed to complete the saponification of unsaponified material since the temperature progressively increases during the passage of the mixture through the heating zone and the saponification reaction proceeds very rapidly as the temperature increases especially if the material being heated has been more thoroughly mixed by passage through the soap pump and connecting pipes.

The invention therefore provides an extremely inexpensive and quick process. Moreover, by reason of the rapidity of flow of the partially or wholly saponified mixture through the coil 32, a high temperature may be imposed thereon sufficient to flash off not only the glycerin and water but other impurities as well, without detrimentally affecting the soap because of its momentary exposure to the elevated heat treatment and the fact that saponification has proceeded under relatively low temperatures and for a relatively long period of time in the kettle or other receptacle.

An important advantage of the present invention is that various types of volatile saponification accelerators, for example, beta naphthol, can be employed in the saponification step even though they are undesirable in the finished soap. Such volatile accelerators can be substantially completely removed from the soap in the evaporating step after they have performed their function of decreasing the time necessary for the saponification step. On the other hand certain non-volatile saponification accelerators have valuable anti-oxidant properties in the finished soap and can be retained therein by the present process even though they are water soluble and would be to a large extent removed by the washing or glycerin removal steps of conventional processes. In either case, in addition to shortening the time necessary for the saponification step, the accelerator assists in substantially completely saponifying the saponifiable material before high temperatures which would injure the same are reached.

The pressure imposed by the pump 26 must be sufficient to allow the desired temperature to be attained. In actual operations for the recovery of glycerin, the temperatures and pressures are ordinarily controlled so that water vapors and preferably some glycerin vapors are formed in the heating device 11 at the pressure therein. Usually it is found desirable to thus vaporize substantially all of the water. Such operation permits more heat to be imparted to the mixture and requires less vaporization with consequent absorption of heat in the evaporating chamber 45. Sufficient heat must be supplied to the evaporating chamber either from the heating device 11 or by other means to maintain a va-

porizing temperature for the glycerin therein. By forming at least part of the vapors in the heating device 32, less additional heat is required to be delivered to the evaporating chamber 45, although in many cases, it is possible to carry on the present process without forming vapors in the heating device 32.

The temperature of the soap deposit in the evaporating chamber will depend upon the amount of glycerin to be recovered therefrom and the nature of the saponifiable material being treated. Certain soaps, for example, those from the lighter fatty acids, will be molten at 455° F., while others require temperatures as high as 565° F. In order to vaporize the glycerin in the evaporating chamber it is preferable that as near a perfect vacuum as possible be maintained in the evaporating chamber and that heat be supplied to the evaporating chamber either by means of a heating jacket 46 or by superheating steam through the pipe 60. Both of these expedients may also be employed.

Thus the present invention provides an improved process which eliminates the expensive and time consuming process of removing volatiles from soap made by conventional processes. The saponifying reaction should be substantially complete before the materials are heated to a glycerin vaporizing temperature in order to prevent possible discoloration of the fatty acids or glycerides. Glycerin can be recovered in a relatively pure and concentrated form and substantially all of the glycerin can be obtained. Also, the soap may be produced in a commercially usable form substantially free from glycerin. The resultant soap from commercial soap making fats is extremely soluble and can be readily reduced to a powdered condition. It absorbs moisture readily and can, therefore, be rehydrated to any desired moisture content and further processed by any of the known means in the art for producing solid or powdered soap.

This application is a continuation in part of my copending application, Serial No. 32,437, filed July 20, 1935.

While I have described the preferred embodiment of my invention, it is understood that I am not to be limited to the details thereof and that the invention may be varied within the scope 50 of the following claims.

What I claim is:

1. A method of making soap by the reaction between a saponifiable material and a saponifying material, which method includes the steps of: saponifying a mixture of said materials under heat while maintaining the temperature below that value at which discoloration due to traces of unreacted saponifiable material will result, thus producing a soap mixture containing soap, glycerin and traces of unreacted saponifiable material; then processing said soap mixture to saponify said traces of unreacted saponifiable material to produce a completely saponified soap product still containing glycerin; then heating said soap product to a higher temperature and subjecting same to a vacuum, the heating being sufficient to cause vaporization of glycerin under said vacuum conditions; separating glycerin vapor from the soap while maintaining the soap in molten, plastic or semi-plastic condition while subjected to said vacuum conditions and promptly, substantially as soon as the soap has been deposited in said vacuum, removing the same without impairing the vacuum.

2. A method of making soap by the reaction

between a saponifiable material and a saponifying material, which method includes the steps of: saponifying a mixture of said materials under heat while maintaining the temperature below that value at which discoloration due to traces of unreacted saponifiable material will result, thus producing a soap mixture containing soap, glycerin and traces of unreacted saponifiable material; then continuously moving a stream of said soap mixture into and through a mixing zone and subjecting same to a mixing action while therein to produce a completely saponified soap product still containing glycerin; then subjecting said completely saponified product to higher temperature and moving same into a chamber maintained under vacuum, the temperature of said soap product being raised to such an extent that glycerin vapors will separate at the low pressure maintained in said chamber; continuously removing the separated vapor from said chamber at such rate as to maintain the vacuum therein and removing said soap from said chamber substantially as quickly as the same is deposited therein and before injury thereto.

3. A process for making soap and separating glycerin which comprises the steps of: mixing saponifiable glycerides with a saponifying reagent in a saponification zone to effect substantial saponification such that heating of the resulting mixture comprising soap, water and glycerin will produce substantially complete saponification before the temperature of the mixture reaches that at which glycerin will separate in vapor form when discharged into a vapor separating zone, maintaining a relatively low temperature during said saponification in said saponification zone insufficient to render the soap molten when anhydrous whereby discoloration due to traces of unsaponified saponifiable material is prevented, withdrawing a stream of said mixture from the saponification zone and rapidly advancing the same under pressure through a separate heating conduit, drastically heating the mixture during its rapid and turbulent flow through said conduit to a temperature greatly in excess of that maintained in the saponification zone and sufficient to separate said glycerin and other impurities when introduced to a vapor separating zone, continuously discharging the mixture into a vapor separating zone while maintaining a temperature sufficient to render the resulting anhydrous soap in a molten condition, continuously withdrawing the glycerin vapors at a rate sufficient to maintain a vacuum therein and continuously removing the anhydrous molten soap from said chamber without impairing said vacuum.

4. A process for making soap and separating glycerin which comprises the steps of: mixing saponifiable glycerides with a saponifying reagent in a saponifying kettle to effect substantially saponification such that heating of the resulting mixture comprising soap, water and glycerin will produce substantially complete saponification before the temperature of the mixture reaches that at which glycerin will separate in vapor form when discharged into a vapor separating zone, maintaining a relatively low temperature during the saponification in said kettle, insufficient to render the soap molten when anhydrous, withdrawing a small stream of said mixture from the saponification kettle and rapidly advancing the same, under pressure, through a separate heating conduit, abruptly elevating the temperature imposed upon the previously saponi- 75

- fied mixture while passing through said separate heating conduit during its rapid and turbulent flow therethrough, sufficient to vaporize said glycerin and other impurities, discharging the 5 soap and vapors into a vapor separating chamber while maintaining the temperature sufficient to render the resultant anhydrous soap in a molten condition, continuously withdrawing the glycerin vapors at a rate sufficient to maintain a vacuum 10 in said vapor separating chamber and continuously and promptly removing the anhydrous molten soap, before injury thereto, from said chamber without impairing said vacuum.
5. The process as defined in claim 4 in which 15 the abruptly elevated vaporizing temperature is limited to such a few minutes as to prevent injury to the soap.
6. The process as defined in claim 4 in which the relatively low temperature and pressure conditions maintained in the kettle during saponification are insufficient to vaporize the glycerin whereby to prevent discoloration of the soap and wherein the temperature abruptly imposed upon the heating conduit is not substantially less than 20 450° F.
7. A process for making soap and removing vaporizable impurities which comprises the steps of: admixing saponifiable and saponifying materials in a saponification zone to produce a mixture of soap and vaporizable impurities; maintaining a temperature and pressure during said saponification insufficient to vaporize said impurities whereby to prevent discoloration; streaming said mixture through a separate and 25 independent heating conduit; vaporizing the unsaponifiable impurities contained in said previously saponified mixture by abruptly and drastically applying a temperature in excess of that maintained in the saponification step and sufficient to render the resultant anhydrous soap in a 30 molten condition, limiting the duration of the drastic heating step for a relatively brief period, and discharging the mixture into a vapor separating zone maintained under vacuum; removing the vapors from said zone and promptly, before 35 injury to the soap, removing the same continuously from the said vapor separating zone without substantially disturbing the vacuum maintained therein.
8. The process as defined in claim 7 which includes a mixing step intermediate the saponification step and the vaporizing step for reacting traces of unreacted saponifiable and saponifying material before introduction of the mixture to the 40 rapid heating zone.
9. A process of making and purifying soap which comprises: adding a saponifying material and a glyceride saponifiable material to a kettle in proper proportions to produce a kettle soap, mixing said materials in said kettle at a temperature not substantially higher than the boiling point of water and below the point at which discoloration due to traces of unsaponified saponifiable material will result to substantially 45 saponify said saponifiable material such that heating of the resulting kettle soap containing glycerin will produce substantially complete saponification before the temperature of the kettle soap reaches that at which glycerin will separate in vapor form when discharged into a vapor separating zone, thereafter pumping a stream of said kettle soap through a heating zone to rapidly heat the same to a temperature sufficiently high to cause substantially all of said glycerin to be separated in vapor form when 50 said stream is introduced into a vapor separating zone and above the melting point of the soap when said glycerin has been separated, introducing the heated stream into a vapor separating chamber maintained under vacuum, continuously withdrawing glycerin vapors, and promptly and continuously withdrawing purified soap from said chamber before the same is damaged by high temperatures and while sealing said chamber from the atmosphere.
10. The process of making soap and rapidly separating glycerin therefrom which comprises: mixing a saponification reagent with a glyceride of a fatty acid in proper proportion, substantially completely saponifying said glyceride at a 55 temperature below the vaporization point of glycerin and below the point at which discoloration due to traces of unsaponified saponifiable material will result, thereafter rapidly heating a stream of the substantially completely reacted mixture out of contact with the air to a temperature which will cause glycerin to be separated in vapor form when said mixture is introduced into a vapor separating zone maintained under vacuum, introducing the heated stream into said vapor separation zone whereby said glycerin is substantially immediately separated in vapor form and anhydrous substantially glycerin free soap is deposited in said chamber, withdrawing vapors at a rate which will maintain said vacuum, and rapidly withdrawing said soap before the same has been damaged by said glycerin separating temperature.
11. A two-stage process for making soap which comprises the steps of: mixing a saponification 60 reagent with a glyceride of a fatty acid in proper proportions, substantially completely saponifying said glyceride at a temperature below the vaporization point of glycerin and below the point at which discoloration due to traces of unsaponified material will result, thereafter elevating the temperature of the mixture to a degree which will cause glycerin to be separated in vapor form when said mixture is introduced into a vapor separating zone, introducing the heated stream into said vapor separation zone whereby said glycerin is substantially immediately separated in vapor form and anhydrous substantially glycerin free soap is deposited in said chamber, withdrawing said vapors from said zone and 65 rapidly withdrawing said anhydrous soap substantially as quickly as the same is deposited in said zone and before the same has been damaged by said glycerin separating temperature.
